UNITED STATES PATENT OFFICE.

ANDERS NILSON, OF CHICAGO, ILLINOIS.

RECORDING SCALE-BEAM.

SPECIFICATION forming part of Letters Patent No. 778,263, dated December 27, 1904.

Application filed March 9, 1904. Serial No. 197,812.

To all whom it may concern:

Be it known that I, ANDERS NILSON, a citizen of the United States, residing at Chicago, in the county of Cook and State of Illinois, have invented certain new and useful Improvements in Recording Scale-Beams; and I do hereby declare the following to be a full, clear, and exact description of the invention, such as will enable others skilled in the art to which it appertains to make and use the same.

My invention relates to a novel construction in recording devices for scales, the object being to provide simple and efficient recording means adapted to record tare and gross and net weights; and it consists in the features of construction and combinations of parts hereinafter fully described and claimed.

In the accompanying drawings, illustrating my invention, Figure 1 is a side elevation of a scale-beam provided with recording devices constructed in accordance with my invention. Figs. 2, 3, and 4 are transverse sections of same on the lines 2 2, 3 3, and 4 4, respectively. Fig. 5 is a plan of a card used in connection with the scale-beam to receive records of weight.

My said invention consists in providing a scale-beam consisting of a bar 1, pivotally mounted on the hangers 3 of the frame and connected with the platform, by means of the rods 2, in the usual manner. The said bar 1 is provided between its ends with a longitudinal slot 4, the parts 5 and 6 above and below said slot 4 forming guides for the balance-weight members 7, 8, and 9, respectively, and being provided with weight-indicating graduations 10, 11, and 12, said graduations 11 and 12 being located on the lower guide, which is provided with a stop 13, the forward edge of which registers with the zero-mark of said graduations 12. The inner end of said slot 4 registers with the zero-mark of the graduations 10 and 11 and is in vertical alinement with a shoulder 14 on said bar. Secured to the guide 5 is a bar 15, provided with notches 16, each having a vertical wall registering with the graduations 10.

The balance-weight member 7 comprises an elongated inverted-U-shaped part 17, having one short flange resting upon the upper edge

of the part 5 of said scale-beam and receiving the notched edge portion of the bar 15, the other flange projecting below the lower edge of said part 5 and carrying a platform 18, which projects through said slot 4. Said member 7 is held against removal by means of a plate 19, mounted thereon and overhanging the front face of said part 5, said plate 19 being provided at its inner end with a recess to form an indicating-finger 20 thereon. In said inverted-U-shaped portion of said member 7 a lever 21 is pivotally mounted between its ends, one end of said lever projecting through a slot in the upper wall of said member and the other end thereof being adapted to enter the notches 16 in the bar 15, said end being normally held at the lower limit of its movement by means of a flat spring 22.

The balance-weight members 8 and 9 are constructed similarly to the member 7 and carry platforms 23 and 24, respectively, and indicating-fingers 25 and 26, but are devoid of levers 21.

Each of said platforms 18, 23, and 24 is provided with a plurality of parallel longitudinal grooves 27 in the upper faces of their free end portions, each of said grooves being located a predetermined distance from the forward face of said bar 1, and the parts 5 and 6 of the latter are provided with outwardly-projecting arms 28, 29, 30, 31, 32, 33, 34, 35, and 36, said arms being of various lengths and being provided in their free ends with vertical openings for the passage of the shanks 37 of button 38, having pointed ends adapted to puncture scale-tickets 39, inserted over said platforms of said balance-weight members. Springs 40 are interposed between the heads of said buttons 38 and the upper faces of said arms to normally hold said buttons at the upper limits of their movement. Said arms and the grooves in said platforms are relatively so arranged that each of the points of said pins of the arms 28, 29, 30, and 31 are in vertical alinement with one of the longitudinal grooves in the platform 18, those of the arms 32 and 33 in alinement with the grooves of the platform 23, and those of the arms 34, 35, and 36 in alinement with the grooves of the platform 24. The number of grooves and pins

90

100

may obviously be increased or diminished, as desired, without departing from the spirit of my invention.

In connection with the devices hereinbefore described I employ a scale-ticket 39, carrying three sets of graduations 41, 42, and 43, said scale 41 comprising four columns of figures reading from "500" to "8,000" in multiples of five hundred, the graduations 42 comprising three columns reading from "0" to "500" in multiples of twenty-five, and the graduations 43 comprising two columns reading from "0" to "1,500" in multiples of fifty. It will be noted that each of said graduations 41, 42, and 43 coincides in its divisions with the graduations 10, 11, and 12, and the size of such ticket and length of each column coincide exactly with the distance between each two pins of any set which are designed to puncture on such column, as will be hereinafter more fully explained.

In operation my device is as follows: Assuming that a wagon to be loaded is to be weighed before and after loading to ascertain net weight of the load, the ticket 39 is inserted over the platform 23 of said balance-weight member 8 and against stops 44 thereon after the said weight has been moved to the balance-point. This brings the columns of the graduations 43 of said ticket over the grooves in said platform, the length of said columns coinciding exactly with the distance between the pins 32 and 33, so that both said pins cannot record at the same time, the wagon having been placed upon the scale-platform and said member 8 moved toward the free end of said bar until the latter is balanced, whereupon the ticket 39 is inserted and the pin then in vertical alinement with the ticket is depressed to puncture the latter, thereby recording the exact weight of the wagon or tare. When the loaded wagon is returned upon the scale-platform, the said member 8 may be returned to the point coinciding with the record on the ticket or may be left at the inner limit of its movement. In the event that the former course is adopted the ticket 39 is first again inserted over the platform 23 and the member 8 then moved until the record on the ticket is in exact vertical alinement with the pin with which such record was made. The ticket is then removed and the member 8 secured in position by means of the set-screw 47 thereon. The balance-weight member 7 is then moved outwardly until it is determined between which two marks of the scale 10 the weight lies, and, assuming that such weight is five thousand seven hundred and twenty-five pounds, the member 7 is moved back until the point of the lever 21 rests in the notch 16 in vertical alinement with the "5,500" mark. The ticket 39 is then inserted and the weight is then recorded on the ticket by depressing the pin 30, and the ticket is then removed. The bal-

ance-weight member 9 is then moved outwardly until the bar 1 or scale-beam proper is balanced, which in this instance would occur when the indicating-finger registers two hundred and twenty-five pounds. The ticket 70 is then inserted over the platform 24 and against the stops 46 thereon, and the finger 35 is then depressed, and thus records this weight on the ticket. By adding the last record to the second the net weight of the load 75 is given. If the member 8 is not moved outwardly to take up tare when the loaded wagon is placed upon the platform, then assuming the weight of such wagon to be one thousand pounds, the second record would be six thousand five hundred pounds instead of five thousand five hundred, and the total six thousand seven hundred and twenty-five pounds. By deducting the tare the net result would be the same. 85

It will be obvious that my invention may be applied to scales of any desired capacity and the specific arrangement herein illustrated and described modified to suit the purpose for which the scale is intended. 90

I claim as my invention—

1. In a scale, the combination with the scale-beam and balance-weight members movable on said scale-beam, of platforms carried by said balance-weight members and adapted to receive scale-tickets, and recording members mounted on said scale-beam at intervals and adapted to register on said scale-tickets, said recording devices being laterally offset at various distances from said scale-beam. 100

2. In a weighing-scale, the combination with a scale-beam provided with weight-indicating graduations, a balance-weight member movable thereon, a platform on said member adapted to receive a scale-ticket, a scale-ticket having printed thereon weight-indicating graduations corresponding in divisions with the graduations on said scale-beam, and recording devices mounted on said scale-beam at intervals and adapted to record on said graduations of said ticket at points corresponding to the weight indicated on said graduations of said scale-beam by said balance-weight member, said recording devices being laterally offset at various distances from said scale-beam. 115

3. In a weighing-scale, the combination with a scale-beam and recording devices mounted thereon, said recording devices being laterally offset various distances from said scale-beam, of a balance-weight member movable on said scale-beam, and means for mounting a scale-ticket therein, said scale-ticket being adapted to be moved into the path of said recording devices to receive weight-records. 120

4. In a weighing-scale, the combination with a scale-beam provided at intervals with projecting arms of various lengths, and recording devices mounted in the free ends of said arms, of a balance-weight member movable on said scale-beam and provided with a pocket adapt- 130

ed to receive a scale-ticket to be carried thereby into the path of said recording devices to receive weight-records.

5. In a weighing-scale, the combination with the scale-beam having weight-indicating graduations, recording devices disposed at intervals on said scale-beam, and a balance-weight member movable on said scale-beam provided with a pocket adapted to receive a scale-ticket and carry same into the path of said recording devices, of said scale-ticket having printed thereon weight-indicating graduations corresponding with the graduations on the scale-beam, said ticket graduations extending through a number of separate columns corresponding in number with said recording devices, each of the columns being disposed in alinement with one only of said recording devices.

20. 6. In a weighing-scale, the combination with a scale-beam having weight-indicating graduations, a plurality of recording devices disposed at regular intervals on said scale-beam, each of said recording devices being offset a different

25 distance from the vertical face of said scale-beam, and a balance-weight member movable on said scale-beam and having a pocket adapted to receive a scale-ticket and carry same into the path of each of said recording devices

30. consecutively, the walls of said pocket being adapted to determine the position of said scale-ticket, said scale-ticket having weight-indicating graduations thereon corresponding with the graduations on said scale-beam and divided into a plurality of parallel divisions each of which is normally held in alinement with one of said recording devices, substantially as and for the purpose described.

7. In a weighing-scale, the combination with a scale-beam having weight-indicating graduations, a plurality of recording devices disposed at regular intervals on said scale-beam, each of said recording devices being offset a different

45 distance from the vertical face of said scale-beam, and a balance-weight member movable on said scale-beam and having a pocket adapted to receive a scale-ticket and carry same into the path of each of said recording devices consecutively, the walls of said pocket being

50 adapted to determine the position of said scale-ticket, of said scale-ticket, having weight-indicating graduations thereon corresponding with the graduations on said scale-beam and divided into a plurality of parallel divisions each of which is normally held in alinement with one of said recording devices, said divisions corresponding in length with the distance between each two adjacent recording devices, whereby each of the latter can record

only in one of said divisions, substantially as 60 and for the purpose described.

8. In a weighing-scale, the combination with the scale-beam, and a plurality of weight-recording devices carried thereby, said weight-recording devices being disposed at regular intervals longitudinally of said beam and laterally offset therefrom at different distances, of a balance-weight member movable longitudinally on said scale-beam, and means carried thereby and coacting with said recording devices for recording weights.

9. In a weighing-scale, having a double scale-beam, a plurality of weight-indicating graduations thereon, recording devices mounted on said scale-beam and disposed at regular intervals relatively to said graduations and offset laterally various distances from said scale-beam, a plurality of balance-weight members movable longitudinally on said scale-beam and indicating on said graduations, and means carried by said balance-weight members and coacting with said recording devices for recording weights.

10. In a weighing-scale, the combination with a scale-beam having a plurality of sets of independent weight-indicating graduations thereon, a plurality of sets of recording devices disposed at regular intervals relatively to said graduations longitudinally of said scale-beams, said recording devices being laterally offset relatively to said scale-beam at different distances, a plurality of balance-weight members corresponding in number with said sets of graduations and each having a pocket adapted to receive a scale-ticket, said pockets being of various depths, of a scale-ticket provided with a plurality of sets of weight-indicating graduations corresponding with said sets of graduations on said scale-beam, said graduations being disposed at various distances from a given edge of said ticket relatively to the depth of each pocket of said balance-weight member and the position of the corresponding recording devices, so that each set of graduations of said ticket is normally brought into position to be acted upon by only one recording device of one set of graduations of said scale-beam whereby tare, fractional and coarse weights are separately recorded on said ticket, substantially as 110 described.

In testimony whereof I affix my signature in presence of two witnesses.

ANDERS NILSON.
